UNITED STATES PATENT OFFICE.

ZEPHANIAH J. MOORE AND HENRY C. SMITH, OF WACO, TEXAS.

COTTON GIN.

Application filed June 19, 1924. Serial No. 721,053.

To all whom it may concern:

Be it known that we, ZEPHANIAH J. MOORE and HENRY C. SMITH, citizens of the United States, residing at Waco, in the county of 5 McLennan and State of Texas, have invented certain new and useful Improvements in Cotton Gins, of which the following is a specification.

This invention relates to cotton gins or 10 other machinery and more particularly to a cleaning means therefor.

Briefly stated, an important object of this invention is to provide a cotton gin having means in communication with the main 15 trash conveying suction pipe or independent fans for expeditiously cleaning in and around the several stands.

A further and equally important object 20 of the invention is to provide a cotton gin with a cleaning means which will not interfere with the normal operation of the machine or the efficient ginning of the cotton.

A further object of the invention is to 25 provide a cleaning means for gins which may be installed on a gin, or other machinery, either during manufacture or while the gin is in use at an extremely low cost and without the exercise of unusual skill.

30 Other objects and advantages of the invention will be apparent during the course of the following description.

In the accompanying drawing forming 35 a part of this application and in which like numerals are employed to designate like parts throughout the same,

Figure 1 is a perspective of a battery of cotton gins equipped with the improved cleaning means, and

40 Figure 2 is a group perspective of the cleaning means detached.

In the drawing, wherein for the purpose 45 of illustration is shown a preferred embodiment of the invention, the numeral 5 generally designates a ginning structure having any desired number of stands 6. As is well known in the art, a distributor 7 is arranged above the several stands and supplies cotton to the feeders of the stands from a separator 8.

The separator 8 has connection with an 50 inlet pipe 14 which sucks the seed cotton up from the wagon in the usual manner. The pipe 15 which connects to the separator may 55 terminate at any desired point and is preferably provided with a flexible portion (not

shown) so that the inlet end of the pipe may be moved about the floor for picking up the overflow cotton, all of which is believed to be clear.

60 The suction is used to pull the cotton from the wagon to a cleaner installed to clean the dirt and trash out of the cotton and empty it out at the bottom of cleaner. We use the air after it passes through cleaner to clean 65 the machinery with our invention. The lint, dirt and trash we clean from machinery will pass through fan and out at discharge.

In carrying out the invention we extend 70 a collector pipe 20 along one side of the distributor 7 and connect the same to the downwardly extending portion of the main suction pipe by any suitable means such as that which is indicated at 21.

75 As plainly illustrated in the drawing, the main collector pipe 20 is provided with a plurality of inlet branches 24, each one of which is arranged adjacent and above one of the stands 6 so that when the flexible hose 26 is connected to one of the branches 80 the inlet end of the hose will be in a position to clean in and around the stand. If desired, the inlet end of the flexible hose 26 may be provided with an enlarged funnel-shaped mouth 28. The flexible hose 26 85 is selectively connected to one of the branches 24 and the remaining branches are closed by caps 30. The caps are adapted to be snugly received in the branches 24 and thereby close the same. Each cap 30 is 90 provided with a more or less tubular attaching portion snugly received in the associated branch 24 and having an annular flange with contacts with the end of the branch 95 to aid in establishing a substantially air tight joint.

95 Fig. 1 also illustrates that the collector pipe 20 extends substantially the entire 100 length of the distributor or to any place it can be used in the gin, and has one end normally closed by one of the caps 30. Of course, the flexible hose 26 may also be connected to the forward end of the collector pipe.

105 In carrying out the invention, the flexible hose 26 is preferably of a length to extend to or nearly to the floor so that it will be capable of gaining access to practically all parts of the gin for cleaning the same.

110 The collector pipe discharges the trash into the main suction pipe 11 so that already existing structure is advantageously utilized.

Herein lies one of the most important features of the invention. It will be seen that by discharging additional trash into the main suction tube 11 the operation or 5 efficiency of the gin is not in any way impaired.

The invention is simple in operation and economical to install. Installation may be made either during manufacture of the gin 10 or at any time thereafter without the exercise of unusual skill.

The inventive idea involved in this application may be carried out by employing a separate fan in which case the collector 15 would be connected directly to the fan.

Having thus described the invention, what is claimed is:

1. In a ginning mechanism, the combination 20 with a plurality of stands, a distributor and a separator having a main trash conveying suction pipe extending therefrom, of a collector pipe supported by said distributor and having communication with the main trash conveying pipe at a point between 25 the separator and the outlet of said main trash conveying pipe, and a flexible hose connected to said collector pipe and having a dust collecting inlet member.
2. In a ginning mechanism, the combination 30 with a plurality of stands, and a separator having a main trash conveying suction pipe extending therefrom, of a collector pipe having communication with the main trash conveying pipe at a point between the 35 separator and the outlet of the main trash conveying pipe, said collector pipe being provided with branches adjacent said stands, and a dust and trash collecting hose adapted to be selectively connected to one of said 40 branches and having an inlet nozzle.
3. In a ginning mechanism, the combination 45 with a plurality of stands, and a separator having a main trash conveying suction

pipe extending therefrom, of a collector pipe having communication with the main 45 trash conveying pipe at a point between the separator and the outlet of the main trash conveying pipe, said collector pipe being provided with branches adjacent said stands, a hose adapted to be selectively connected 50 to one of said branches and having an inlet nozzle for collecting dust and trash, said ginning mechanism also being provided with a distributor extending over said stands and forming a support for said collector pipe.

4. An attachment for gins comprising a collector pipe having means whereby the same may be supported by the distributor of a gin and having communication with the 60 main trash conveying suction pipe of the ginning mechanism at a point between the inlet and outlet ends thereof, said collector pipe being provided with branches adjacent the stands of the gin, and a hose adapted to 65 be connected to one of said branches for use in cleaning about the stands.

5. An attachment for ginning mechanisms comprising a collector pipe adapted for communication with the main trash conveying suction pipe of a ginning mechanism, and being provided with inlet branches adjacent the several stands of the ginning mechanism, closures for said branches, and a flexible dust collecting hose adapted to be 70 selectively connected to one of said branches.

6. The construction set forth in claim 5, said collector pipe being adapted to be supported by the distributor of a ginning mechanism and extending for the major 75 portion of the length of the distributor.

In testimony whereof we affix our signatures this the 17 day of April, 1924.

Z. J. MOORE.
H. C. SMITH.
